UNITED STATES PATENT OFFICE

2,428,207

FASTENER FOR CLOSURES

Michael Dzurinda, Farrell, Pa., assignor to
L. R. Landay, Farrell, Pa.

Application December 1, 1944, Serial No. 566,099

1 Claim. (Cl. 292—340)

1

My invention relates to fasteners for closures, and more particularly to improvements in hasps and keepers therefor.

The primary object of my invention is to provide an efficient, theft-proof hasp and keeper adapted to compensate for sagging of structure to which the same are attached and which are comparatively simple in construction, easy to apply, and inexpensive to manufacture.

Other and subordinate objects are also comprehended by my invention, all of which, together with the precise nature of my improvements, will be readily understood when the succeeding description and claim are read with reference to the drawings accompanying and forming part of this specification.

In said drawings:

Figure 1 is a view in front elevation of my improved fastener in a preferred embodiment thereof,

Figure 2 is a view in side elevation,

Figure 3 is a view in horizontal section taken on the line 3—3 of Figure 1,

Figure 4 is a view in front elevation of a modified embodiment of hasp,

Figure 5 is a view in side elevation, and

Figure 6 is a view in horizontal section taken on the line 6—6 of Figure 4.

Reference being had to the drawings by numerals, and first to Figures 1 to 3 thereof, my improved fastener, in the illustrated preferred embodiment thereof, comprises a hasp 1, and a keeper 2 for attachment, as presently described, to a door 3, and a door frame structure 4, or the like.

The hasp 1 comprises a pair of long and relatively shorter hasp leaves 5, 6 hinged together, as at 7, at one end thereof, for attachment of the short leaf 6 to the door 3, as by screws 8, so that the long leaf 5 may be swung into closing position with its free end portion overlapping the frame structure 4 and said leaf overlying the leaf 6 and thereby preventing access to the screws 8. The free end portion of the leaf 5 is provided with the usual longitudinally extending slot 9 therein.

The keeper 2 comprises a pair of elongated hinge leaves 10, 11 hinged together, as at 12, at one end thereof, to arrange the leaf 11 in front of the leaf 10 in overlying position relative thereto. The leaves 10, 11 are adapted to be attached to the frame structure 4 to extend endwise vertically of said structure with the hasp leaf 5 overlying the leaves 10, 11 substantially midway of the ends of the same. For attaching the leaves 10, 11 to the frame structure 4, screws

2

13, 14 are suitably extended through the upper and lower ends of the leaf 10 and which, as will be clear, are concealed by the overlying front leaf 11, it being understood that the front leaf 11 is of the same length as the rear leaf 10 for that purpose. An eye member 15 for extension through the slot 9 is mounted in the leaves 10, 11 for vertical sliding movement and rotation therein, said member 15 having a shank 16 extended through registering slots 17, 18 provided in the leaves 10, 11, respectively, to extend lengthwise thereof in the longitudinal center of the same. A washer 19 is provided on the shank 16 in the rear of the leaf 10 with said shank upset, as at 20, against the washer, and whereby the eye member is secured in said leaves 10, 11. The leaf 10 is provided with a forwardly offset intermediate portion 21 spaced from the frame structure 4 to provide clearance for the washer 19 so that said washer may slide freely behind said leaf 10. As will be seen, the eye member 15 and washer 19 form a sliding lock preventing separation of the leaves 10, 11.

The manner in which the described embodiment of the invention is adapted to be used and to operate will be generally understood from the foregoing description. Suffice it to explain that if either door 3 or frame structure 4 sags, the slot 9 of the hasp leaf 5 may be accurately registered with the eye member 15 by sliding said member vertically, and appropriately rotating said member. Since, as shown in the drawings, the slots 17, 18 are arranged crosswise of the slot 9, the eye member 15 may be rotated into a position intermediate said slot to latch the hasp leaf 5 in case the usual padlock, not shown, is not available.

In the modified embodiment of the invention shown in Figures 4 to 6, the hasp comprises a long leaf 22 hinged, as at 23, to a short leaf 24, the long leaf 22 having the usual longitudinal slot 25 in the free end thereof for the insertion therethrough of the usual staples 26 attached to the door frame structure 27 by means of a base plate 28 and screws 29. The hasp is secured to the door 30 for vertical sliding movement and limited vertical swinging movement relative thereto and by the following means. The short hasp leaf 24 is provided with an intermediate transversely extending bend 31 whereby said leaf is provided with a free end portion 32 offset rearwardly of the remainder of said leaf. The side edges of said leaf 24 are notched, as at 33, in line with the bend 31 to reduce the length of the bend for a purpose presently apparent. An elongated

mounting plate 34 is provided for attachment to the door 30 to extend endwise vertically. Screws 35 secure the end portions of said plate 34 to said door. Intermediate said end portions, the plate 34 is provided with a vertically extending slot 36 and is bent to provide a forwardly offset portion 37 spaced forwardly of the door 30. The hasp leaf 24 is inserted through the slot 36 with the bend 31 extending through the slot and the end portion 32 underlying the forwardly offset portion 37.

As will be seen, in the modified embodiment of the invention, the hasp leaf 24 may be slid vertically in the mounting plate 34 or swung vertically in the slot 36 to correspondingly adjust the hasp leaf 22 and compensate for sagging of either the door 30 or the frame structure 21 so that the slot 25 may be positioned over the staple 26 regardless of the extent to which said door 30 or frame structure 21 has sagged.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claim.

What I claim is:

A fastener for a hinged slotted hasp comprising a pair of elongated leaves, one for attachment to a fixed structure and the other hinged at one end to one end of the attached leaf for swinging into overlying relation thereto, the hinged leaf having

a longitudinal slot therein and the attached leaf having a forwardly offset intermediate portion adapted to provide a clearance between the same and said structure and provided with a longitudinal slot therein adapted to register with the slot in the hinged leaf, and an eye member for projection through the slot in the hasp and having a shank extending through the slots in said leaves when said slots are registered and provided with a washer fixed thereon behind said offset portion to dispose the same in said clearance, said shank being slidable in the slots of said leaves whereby the eye member may be adjusted along said leaves to facilitate extension of the same through the slot in the hasp, and said shank being rotatable in the slots of said leaves, whereby the eye member may be turned crosswise thereof to prevent the hinged leaf from swinging away from the attached leaf and whereby said eye member may also be turned crosswise of the slot in the hasp to fasten the hasp thereto.

MICHAEL DZURINDA.
